(57) **CLAIM**

The ornamental design for a cooler cart cover, as shown and described.

DESCRIPTION

FIG. 1 is a front and top perspective view of a cooler cart cover, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partially enlarged view thereof, taken from FIG. 1;

FIG. 10 is a partially enlarged view thereof, taken from FIG. 1;

FIG. 11 is a partially enlarged view thereof, taken from FIG. 1;

FIG. 12 is a partially enlarged view thereof, taken from FIG. 2; and,

FIG. 13 is a partially enlarged view thereof, taken from FIG. 2.

The dashed lines in the figures illustrate portions of the cooler cart cover that form no part of the claimed design. The dash-dot broken lines in FIGS. 1, 2, and 9–13 are included to show partially enlarged views only and form no part of the claimed design.

1 Claim, 13 Drawing Sheets
